UNITED STATES PATENT OFFICE.

ROBERT H. MARRIOTT, OF BROOKLYN, NEW YORK, ASSIGNOR TO THE UNITED WIRE-LESS TELEGRAPH COMPANY, OF NEW YORK, N. Y., A CORPORATION OF MAINE.

ANTENNA.

972,004.

Specification of Letters Patent.

Patented Oct. 4, 1910.

Application filed April 8, 1910. Serial No. 554,294.

To all whom it may concern:

Be it known that I, ROBERT H. MARRIOTT, a citizen of the United States, residing at Brooklyn, in the county of Kings and State 5 of New York, have invented certain new and useful Improvements in Antennæ; and I do hereby declare the following to be a full, clear, and exact description of the invention, such as will enable others skilled in 10 the art to which it appertains to make and use the same.

My invention relates to antennæ for use in wireless communication and has for its object to provide a plurality of antennæ 15 having different natural periods, any one or more of which may be used for receiving purposes; while all the antennæ may act together as a unit for sending purposes. This construction permits the operator to 20 tune by simply connecting in the circuit that particular antenna to which the receiving tuner circuits best respond when the wave from the sending station impinges thereon; and it enables the operator to lessen the 25 interference by grounding those antennæ which respond best to the interfering waves or impulses. Furthermore, while the several receiving antennæ are practically insulated from each other by short spark gaps 30 when receiving, they are practically connected together by means of said gaps when traversed by the high voltage sending currents, so that in sending the combined antennæ act together, and like one large antenna.

My invention will be better understood by reference to the accompanying drawings forming a part of this specification in which the figure is a diagrammatic view of the 40 antennæ wires, spark gaps, switches, sending apparatus, receiving apparatus, and connections, constituting my invention.

In said drawings the numerals 1 to 31 inclusive, represent the individual wires making up the several receiving antennæ individually designated by the letters A, B, C, D, E, F and G, and which are connected during sending by the spark gaps $g' g'$ to constitute a single antenna. For example 45 A represents a receiving loop antenna made up of the wires 1, 2 and 3. Likewise the re-

ceiving loop antennæ B, C, E, F, and G, are made up respectively of the wires 6, 7, 8; 11, 12, 13; 18, 19, 20; 23, 24, 25; 28, 29, 30; while receiving loop antennæ D is made up 55 of wires 16, 31 and 17 with the additional wires 4, 5, 9, 10, 14, 15, 21, 22, 26 and 27. It will thus be seen, therefore, that loop D is not a pure loop like the others, since it has these various extra wires of different 60 lengths attached to it. These wires, of course, increase the capacity and inductance of the loop D and thereby give it a longer natural period than the other loops. From actual operations that have been carried out 65 the natural periods of the various loops seem to increase in the following order— A, B, C, E, F, G, and D.

$g' g'$ represent the spark gaps that serve to insulate the antennæ A, B, C, D, E, F, 70 and G one from the other. The letters g represent small spark gaps which insulate the various antennæ from conductor 32 when receiving and connect the antennæ with said conductor when sending. 75

$S_1, S_3, S_6, S_8, S_{11}, S_{13}, S_{16}, S_{17}, S_{18}, S_{20}, S_{23}, S_{25}, S_{28}$, and S_{29} , represent single pole double throw switches which serve to connect any one or more of the wires 1, 3, 6, 8, 11, 13, 16, 17, 18, 20, 23, 25, 28 and 29 to 80 either of the conductors 33 or 34. Conductor 33 is connected by switch B_3 through a variable inductance 40, in inductive relation with the inductance 41 joined to a variable condenser 42. A ground 43 is also joined 85 to the inductance 40, through the variable condenser 44.

From what has been so far disclosed it is evident that the horizontal wires 2, 7, 12, 19, 24 and 30, as well as the spark gaps $g' g'$ 90 may be so located with respect to the various vertical wires as to form individual loop antennæ having any desired natural periods, and that any one or more of these antennæ may through the switches S_1 , to S_{29} , be 95 joined at will to the ground 43 of the receiving circuit or to the wire 34 connected to a ground as will be described. The receiving circuit also comprises the following parts in which, 46 represents a condenser, 100 47 a detector, and 48 a telephone receiver preferably joined as shown to complete the

receiving circuit. 34 represents a conductor connected through switch B_2 to a ground 45, preferably through a variable inductance 46 as shown. The wire 32 connects 5 through a variable inductance 50 to a ground 51. The transmitting circuit comprises the spark gap 55, condenser 56, transformer 57, 58, key 59, switch 60, and generator 61 all as will be readily understood.

10 It is apparent when switch 60 is closed, switches B_2 and B_3 opened and key 59 depressed, that the transmitter current flows via the conductor 32 and spark gaps g and g' into all parts of the antennæ, so that 15 the action of said antennæ is practically the same as that of a continuous conductor. On the other hand if key 59 is opened and switches B_2 and B_3 are closed it is found that by connecting one side of some one of 20 the loops, for example loop C, by means of its switch S_{11} to the primary of the receiving tuner and the other side of said loop C as by means of switch S_{13} to the ground; that the tuning coils and condensers can be 25 so adjusted that the signals from some one or more stations will come in louder than when any of the other loops are similarly connected. For other stations it will be found some other loop will bring the signals 30 in louder. Again it is found that when receiving comparatively short waves on one of the shorter antenna loops and a station sending a longer wave length interferes, the longer wave length signals can be cut out or 35 cut down by grounding some one of the longer loops through wire 34 without materially diminishing the signals from the station sending the short waves and vice versa. Further, if while the static charge is so 40 strong as to jump a $\frac{1}{8}$ inch spark gap in conductor 32, switches B_2 and B_3 being open; we close switch B_2 and ground loop G through wire 34 it is found if other loops are connected to the receiving instrument by 45 closing switch B_3 and some of the switches S, S_3 etc., that signals can be read from low powered stations over five hundred nautical miles distant without being interfered with by static charges.

50 It is evident that changes in the details of construction and in the arrangement of parts may be made by those skilled in the art without departing from the spirit of my invention, and therefore I do not wish to be limited to such features except as may be required by the claims.

What I claim is:—

60 1. In a wireless telegraphic apparatus the combination of a sending means; a receiving means; a plurality of receiving antennæ of different inductances and capacities, and, therefore having different natural periods connected to said receiving means; and connections with said sending means by which 65 said antennæ may be employed as a single

antenna when sending, substantially as described.

2. In a wireless telegraphic apparatus the combination of a sending means; a receiving means, a plurality of receiving antennæ 70 having different natural periods connected to said receiving means; and automatic connections with said sending means by which said antennæ may be employed as a single antenna when sending, substantially as de- 75 scribed.

3. In a wireless telegraphic apparatus the combination of a sending means; a receiving means; a plurality of receiving antennæ having different natural responsive periods; 80 and means for so connecting said antennæ with said sending means as to cause said antennæ to act as a single antennæ which sending, substantially as described.

4. In a wireless telegraphic apparatus the 85 combination of a sending means, a receiving means, a plurality of receiving antennæ having different natural responsive periods; and automatic means for so connecting said antennæ with said sending means as to cause 90 said antennæ to act as a single antenna while sending, substantially as described.

5. In a wireless telegraphic apparatus the combination of a plurality of antennæ of different inductances and capacities and 95 therefore having different natural periods; and means adapted to insulate said antennæ from each other for low potentials and to electrically connect said antennæ together for high potentials, substantially as de- 100 scribed.

6. In a wireless telegraphic apparatus the combination of a plurality of antennæ having different natural periods; and automatic means adapted to insulate said antennæ from each other for low potentials and to electrically connect said antennæ together for high potentials, substantially as de- 105 scribed.

7. In a wireless telegraphic apparatus the combination of a plurality of receiving antennæ having different natural periods; air gaps for insulating said antennæ from each other; a ground connection, and air gaps for insulating said antennæ from said ground connection, substantially as de- 110 scribed.

8. In a wireless telegraphic apparatus the combination of a plurality of receiving antennæ having different natural periods; air gaps for insulating said antennæ from each other; a ground connection, air gaps for insulating said antennæ from said ground connection, a second ground connection; and means for connecting any of said antennæ to said second ground connection, substantially as described.

9. In a wireless telegraphic apparatus the combination of a plurality of receiving antennæ having different natural periods; air 130

gaps for insulating said antennæ from each other; a sending apparatus; a ground connection associated with said sending apparatus; connections between said sending apparatus and said antennæ; air gaps between said antennæ and said connections; a second ground connection adapted to be joined with said antennæ; and a receiving apparatus

joined to said antennæ, substantially as described.

10

In testimony whereof, I affix my signature, in presence of two witnesses.

ROBERT H. MARRIOTT.
